UNITED STATES PATENT OFFICE.

FRIEDRICH BEZNER, OF DELAVAN, ILLINOIS.

IMPROVEMENT IN WASHING-MACHINES.

Specification forming part of Letters Patent No. 131,327, dated September 17, 1872.

To all whom it may concern:

Be it known that I, FRIEDRICH BEZNER, of Delavan, in the county of Tazewell and in the State of Illinois, have invented a Washing-Machine; and do hereby declare that the following is a full, clear, and exact description thereof, reference being had to the annexed drawing making a part of this specification, in which like letters of reference refer to like parts, and in which—

Figure 1 represents an elevation, seen from the side, the side piece removed; Fig. 2, end elevation, with end piece removed to give full view; Fig. 3, a plan.

This invention consists of a wash-board, composed of strips of tin or other non-corrosive substance, a , fastened transversely on a web, a' , which runs over rollers D^1 D^2 , one of which is placed near either end of the wash-box A B C, and rotated by a wheel on the end of one of the rollers, D^2 . On this endless wash-board a a' , so to speak, rest several rubbing-blocks, E E E E, whose under surfaces are corrugated, and are propelled back and forth on the clothes, which lie upon the wash-board a a' , lengthwise of the wash-box A B C, by rods h h h , severally attached to the crank J, which is revolved by a pinion, I, which engages with a spur-wheel, H, on the end of the nearest roller, D^2 ; which crank also gives a similar motion—back and forth—to a foot-bar, G, and foot f, which also rests upon the clothing to be washed and the board a a' , and presses the former under the rubbing-blocks E E E E. A A are the ends of the wash-box, which are square, C C being the sides, and B the bottom. D^1 D^2 are two rollers, which carry an endless web, a' , whose surface is entirely covered by transverse strips of tin, a , corrugated lengthwise, similar to and intended to act like the corrugations of the common hand wash-board. In front of and on a level with the so called wash-board a a' is a horizontal feeding-platform, d, extending to the roller D^2 . E E E E are four oscillating rubbing-blocks, each having a curved lower surface, thicker in the middle and tapering toward the ends; or an arc of a circle, of which their point of suspension or pin in the arms F may be considered the center. Each block E has a stem, g, pivoted loosely in a pin in the arms F F, &c., which latter extend horizontally from

a common transverse horizontal rod or pivot, n, to the rear of the box A B C, and a rod, h h h , extends from each stem g g g to a transverse crank, J, pivoted in the upper and forward end of said box. At the outer end of said crank is affixed a pinion, I, which engages with the motive spur-wheel H, which is provided with a handle, z, both wheels being on the exterior of the box. To this crank J is also attached a presser-foot, G, which extends obliquely forward and downward, and terminates in a foot, f, which rests upon the clothes and the wash-board a a' immediately under the front of the rubbing-blocks E E. Under the ends of the arms F F is a crank-like rod, K, pivoted in either side of the box, which terminates, near the wheel H, in an arm, i, from which a rod, k, extends below the axle of said wheel, and terminates in an elbow, y, which, at each revolution of the wheel H, is depressed by a pin, l, on the nave or hub of said wheel, or a crank, so as to lift the rubbing-blocks E E E at intervals.

The operation of this washing-machine is as follows: The usual hot water and soap being introduced, and the handle z turned from left to right, or as the hands of a watch rotate, the wheel H on the end of the axle of roller D^2 causes the latter to pass the endless web a' and its attached strips a a a backward under the rubbing-blocks E E E E at the same time that the clothes are passed along the feeding-platform d under the foot f, which pushes them forward under the rubbers E E. In the meantime the wheel H rotates the pinion I on the end of the crank J, giving simultaneous motion to the attached foot f, just mentioned, and the rubbing-blocks E; the latter by means of the rods h h h h attached to the stems g g g g of the former, thus pushing the former back and forth over the clothes, well rubbing them by means of their before-mentioned corrugated lower surfaces upon the progressive endless wash-board a a' , said rubbers E E being weighted downward for this purpose by their respective arms F F F F. At the same time, also, the wheel H, at every revolution, depresses the rod k and the elbow y attached to the arm i of the crank-shaped rod K, which, by its horizontal bent portion, on which all of the arms F F rest, raises the latter at each revolution to facilitate the passage of the clothes under

the rubbers E E in case the clothes should happen to collect at one spot in a mass or lump.

What I claim as my invention is—

1. The upright lever G and its actuating-crank J, in combination with the endless wash-board a' a', rollers D¹ D², and wheel H, substantially as described.

2. The combination of the box A B C, endless wash-board a' a', the rubbing-blocks E E, stems g g g, arms F F F F, pivot-rod n, substantially as described.

3. The combination of the arms F F F F, crank or lifter K, its arm i, rod k connected with wheel H, the wheel H, pinion I, crank J, rods h h h united to the stems g g g, substantially as described.

In testimony that I claim the foregoing washing-machine I have hereunto set my hand this 16th day of February, 1872.

FRIEDRICH BEZNER.
